UNITED STATES PATENT OFFICE.

HERBERT P. SEYMOUR, OF HARTFORD, CONNECTICUT, ASSIGNOR, BY MESNE ASSIGNMENTS, TO THE AMERICAN BICYCLE COMPANY, OF JERSEY CITY, NEW JERSEY, AND NEW YORK, N. Y.

BACK-PEDALING BRAKE.

SPECIFICATION forming part of Letters Patent No. 662,881, dated November 27, 1900.

Application filed April 23, 1898. Serial No. 678,556. (No model.)

To all whom it may concern:

Be it known that I, HERBERT P. SEYMOUR, a citizen of the United States, and a resident of Hartford, in the county of Hartford and State of Connecticut, have invented certain new and useful Improvements in Back-Pedaling Brakes, of which the following is a full, clear, and exact description, whereby any one skilled in the art can make and use the same.

10 The object of my invention is to construct a gear-driven velocipede or vehicle of this class with a brake which is applicable to this special form of driving mechanism and one that is simple and positive in action.

15 To this end my invention consists in the device as a whole, in the combination of parts making up the device, and in the details and their combination, as hereinafter described, and more particularly pointed out in the 20 claims.

Referring to the drawings, Figure 1 is a view in side elevation of a gear-driven bicycle in which my invention is embodied and of a class to which it is applicable. Fig. 2 is a 25 view in side elevation, on an enlarged scale, of the rear end of the frame, of the connecting-shaft with its driving-gear, and the gear on the hub of the driving-wheel, parts being broken away to show construction. Fig. 3 is a view, 30 on an enlarged scale, showing the connecting-shaft gear and the casing of the brake appurtenant to it. Fig. 4 shows in edge elevation and with parts broken away the several elements of the brake as removed from the casing. Fig. 5 is a view in front elevation of the 35 brake-casing and in end elevation of the ball-bearing cone. Fig. 6 is a detail view of the rear end of the connecting-shaft. Fig. 7 is a detail view, in front elevation, of the rear 40 end of the connecting-shaft. Fig. 8 is a view in transverse section through the parts of the brake looking from the right as parts are shown in Fig. 3 and showing the brake out of operation. Fig. 9 is a like view in section 45 on the same plane, showing the brake in operation, the ring being expanded against the shell. Fig. 10 is a detail view in lengthwise section through the rear end of the connecting-shaft, showing a modified form of the in-

vention. Fig. 11 is a detail view in cross-section through this last-described form.

In the accompanying drawings the letter *a* denotes the frame member, on which bearings are provided for a connecting-shaft *b*, the latter being driven by any suitable means, 55 as a crank-shaft and pedals, and intermediate connecting mechanism, as gear-wheels.

On the projecting end of the frame member *a* a brake-drum *c* is held by screwing it upon the threaded end of the frame member, 60 where it is held by means of a lock-nut *c'*, although any other convenient means of securing the brake-drum to the frame member may be used. This brake-drum also serves as a case for the balls provided as a bearing 65 for the connecting-shaft *b*.

A cone *d* is secured to the connecting-shaft, as by means of a key or spline *d'*, which is located in key-seats in the respective parts in the ordinary manner. This cone has a periphery, preferably cylindrical in outline, with a flange *d*² on one side to assist in holding an expanding ring *e* loosely upon it. The cone has also a socket or opening *d*³ cut across its edge to receive a lug or arm *f'*, which projects into it from the gear-wheel *f*. Near one side of this socket there is also a shoulder *d*⁴, formed on the periphery of the cone and against which one end *e*¹ of the expanding ring *e* rests. The other end *e*² of the ring *e* is formed 75 to fit a socket in the side of the arm *f'*, as illustrated in Figs. 8 and 9 of the drawings.

Near the end of the connecting-shaft *b* there is a thin flange *b'*, beyond which the enlarged end of the shaft is formed of two different 85 diameters, the larger being threaded to receive a bushing *g*, which is screwed firmly upon it. The gear-wheel *f* fits upon and has a limited rotary movement on this bushing, which is located within the gear-wheel, as 90 illustrated in Figs. 2 and 4 of the drawings. Outside of the bushing and gear-wheel is a nut *h*, larger in diameter than the bushing, so that its edge overlaps the hub of the gear-wheel and serves to hold the latter between 95 the flange *b'* and the nut *h*, forming a sort of groove or channel in which the gear-wheel has a limited rotary movement without being

permitted to move lengthwise of the connecting-shaft. There is a socket b^3 formed in the edge of the flange to enable the arm f' to extend across this flange into the socket in the 5 cone and within the brake-drum. The inner surface of the socket in the brake-drum is preferably cylindrical and formed in a plane parallel to the axis of the connecting-shaft, as illustrated in Figs. 5, 8, and 9 of the drawings.

In Figs. 3 and 4 the brake-drum c , the expanding ring e , and the cone d , with the sockets d^3 , are clearly shown. When the parts are properly assembled, as illustrated in the section in Fig. 2, the rear surface, with respect to its direction of rotation of the arm, rests against the edge of the socket d^3 , preferably formed on a radial line, (or it may be slightly undercut,) so that the rotary movement of 15 the connecting-shaft in a direction to drive the vehicle forward carries with it the cone and the gear f by reason of the interengagement of the arm on the gear and the socket d^3 in the cone. The expanding ring e is in 20 its contracted condition and moves freely within the brake-drum rotating with the cone and the gear. 25

As soon as the forward rotation of the connecting-shaft is stopped while the vehicle is 30 moving forward the momentum causes the gear-wheel f to continue in rotation, but under the impulse of the gear-wheel i , which is fast to the driving-wheel and continues to rotate with it and not under any force applied 35 through the connecting-shaft. This continued rotary movement of the gear-wheel f while the cone d is retarded in its rotation causes the arm f' to thrust against the end e^2 of the expanding ring, the rotation of which 40 is retarded by the engagement of the end e' of the ring with the shoulder d^4 on the cone, and this causes the ring to forcibly expand against the inner surface of the brake-drum, thus applying the brake to retard the further 45 rotation of the driving mechanism.

In the modified form of the device shown in Figs. 10 and 11 the connecting-shaft k is tubular, the fork side l extending through the connecting-shaft and supporting it at its rear 50 end. A ball-case k' is secured to the end of the connecting-shaft, and the cone l' is supported on the fork side l . The gear m is mounted on the shaft k in a manner to have a limited reverse rotary movement thereon. 55 The brake-drum n is secured against rotation on the fork side l , and the brake-ring o surrounds the drum, the end o' of the ring having a lug fitting a recess in an arm m' , projecting from the inner surface of the gear-wheel m . In this form of the device when 60 force is applied to the connecting-shaft k to retard its movement the gear-wheel m continues to rotate under the impulse of the driving-wheel caused by the forward movement 65 of the machine. This continued rotary movement of the gear-wheel m while force is applied to retard the rotary movement of the

connecting-shaft k causes the arm m' on the gear-wheel to pull upon the end o' of the ring o , the rotation of which is prevented by the 70 engagement of the lug o^2 with the recess in the ball-case k' . This causes the ring to contract against the outer surface of the brake-drum n , thus applying the brake to prevent the further rotation of the driving mechanism. 75

The brake mechanism is shown herein as applied to the rear end of the connecting-shaft; but such location on said shaft is not essential to the invention, as the brake would operate wherever the shaft and gears or like 80 power-transmitting parts can be readily arranged with relation to each other, as described.

In the form shown in Figs. 8 and 9 the arm on the gear projects into a recess in the cone; 85 but such recess is not essential, as engaging shoulders on the two parts would serve the same purpose within my invention.

I claim as my invention—

1. In a gear-driven vehicle, a connecting-shaft included in the driving means, a recess in the shaft, a gear mounted on and driven by said shaft and having a limited reverse rotary movement independent thereof, an arm thereon of a width less than the width of said 95 recess, a brake-drum secured to a frame member, a brake-ring carried by the shaft with one end connected to the shaft and the other connected to the gear which is movable thereon, and a driving-wheel of the vehicle operatively connected with said gear on the connecting-shaft.

2. In a gear-driven vehicle, a tubular frame member, a connecting-shaft extending through said member, a cone on said shaft 105 having a recess, a gear mounted on and driven by said shaft and having a limited reverse rotary movement independent thereof, an arm extending from the gear into and of a width less than said recess, a brake-drum secured 110 to a frame member, a brake-ring located on the cone with one end in the path of movement of said arm and the other end resting against a shoulder on the cone, and a driving-wheel of the brake operatively connected with 115 said gear on the connecting-shaft.

3. In a gear-driven vehicle, a connecting-shaft included in the driving means, a bevel-gear mounted on and having a limited reverse rotary movement independent of said shaft 120 and driven thereby, an arm extending from the back of said gear into a brake-drum, a brake-drum secured to a frame member, a brake-ring with one end located in the path 125 of movement of said arm and the opposite end resting against a shoulder on the connecting-shaft, and a driving-wheel of the vehicle having a bevel-gear in mesh with the bevel-gear on the connecting-shaft.

4. In a gear-driven vehicle, a connecting-shaft included in the driving means, a cone secured to said shaft, a bevel-gear located in a peripheral recess in the connecting-shaft and having a limited reverse rotary move- 130

- ment independent thereof, an arm projecting from the back of said gear into a brake-drum, the brake-drum secured to a frame member, a brake-ring located in the drum with one end in the path of movement of said arm and the opposite end resting against a shoulder on the shaft, and a driving-wheel of the vehicle having a bevel-gear in mesh with the bevel-gear on the connecting-shaft.
- 10 5. In a gear-driven vehicle, a connecting-shaft included in the driving means, a cone secured to the shaft and having a recess in the periphery thereof, a bevel-gear secured to the shaft and having an arm extending from the back of said gear into the recess in the cone, a brake-drum secured to the frame of the machine, a brake-band supported by the cone and with one end in engagement therewith and the opposite end resting against the

arm on the gear, and a driving-wheel of the 20 vehicle having a bevel-gear in mesh with the gear on the connecting-shaft.

6. In a gear-driven vehicle, a connecting-shaft included in the driving means, a bevel-gear mounted on and having a limited reverse 25 rotary movement independent of said shaft and driven thereby, an arm extending from said gear into a brake-drum, the brake-drum secured to a frame member, a brake-ring with one end located in the path of movement of 30 said arm and the opposite end resting against a shoulder on the connecting-shaft, and a bevel-gear in mesh with the bevel-gear on the connecting-shaft.
